ATTORNEY

UNITED STATES PATENT OFFICE.

JAMES N. TREE, OF DETROIT, MINNESOTA.

BOLSTER EXTENSION.

1,337,416.

Specification of Letters Patent. Patented Apr. 20, 1920.

Application filed December 10, 1918. Serial No. 266,078.

To all whom it may concern:

Be it known that I, JAMES N. TREE, a citizen of the United States, residing at Detroit, in the county of Becker and State of Minnesota, have invented certain new and useful Improvements in Bolster Extensions, of which the following is a specification.

This invention has relation to attachments for log hauling vehicles, and has for an object to provide means whereby the normal capacity of the vehicle may be increased.

Another object of the invention is to provide attachments for log hauling vehicles of a nature to be secured to the ends of the bolsters whereby to prolong the length of the bolsters thereby permitting a greater lateral expanse of the vehicle to support an additional number of logs.

In addition to the foregoing my invention comprehends improvements in the details of construction and arrangement of the parts to be hereinafter more fully described and particularly set forth in the appended claims.

Figure 1, is a view in side elevation of my attachment applied to one end of a bolster.

Fig. 2, is a view of the device in plan, and

Fig. 3, is a view of the device in longitudinal section.

With reference to the drawings, 10 indicates one end of a bolster such as is used in the construction of either wheel supporting vehicles, or sleds, adapted for hauling logs. The bolsters are extended transversely of the vehicle or sled in longitudinally spaced relation, and the logs are supported on the bolsters in a position longitudinally of the vehicle. For the purposes of my invention each end of each bolster is provided with a vertical opening 11.

My improvement comprises a pair of hingedly connected sections 12 and 13, the section 13 comprising a plate 14 having centrally formed thereon a stout stud 15 to enter the opening 11 of the bolster. The plate is also formed upon one edge with a pair of spaced lugs 16 having alined apertures in which to receive pins 17.

The section 12 of the device comprises a plate 18 of a width slightly less than the width of the bolster and of any desired length provided upon one end with an apertured lug 19 which is disposable between the lugs 16 to receive the pin 17 and thereby hingedly connecting the sections 12 and 13 together. The plate 12 is formed upon its

under side with an abutment 20 at the end of the plate bearing the lug 19 and the outer vertical edge of the abutment is inclined to receive the inclined end of the bolster. If desired the end of the bolster may be reinforced by means of a casting 21 which may be formed with a leg 22 upon which the abutment 20 may rest thus forming a secure bearing and considerably increasing the durability of the device.

The opposite end of the plate 18 is provided upon its under side with an enlargement 23 which may be of a hollow construction in which event the lower side of the enlargement is formed with an opening 24 in vertical alinement with an opening 25 formed in the plate 18. If desired, the abutment 20 may be similarly formed of open work construction to let the amount of metal necessary in the construction of the device without sacrificing any of the strength thereof. To further brace the section 18, a rib 26 may be formed upon the under side of the plate as indicated.

In use, and when it is necessary to extend the width of the vehicle to support an additional number of logs, the section 12 is disposed in an outwardly extending horizontal position with the abutment 20 bearing against the end of the bolster as indicated in the drawings. A stake (not shown) may be inserted in the openings 25 and 24 at the outer end of the device to permit the logs to be piled one upon another. Thus it will be seen, that by providing a device of this character upon each end of each bolster the width of the vehicle may be increased considerably to support a greater number of logs thereby increasing the capacity and value of the vehicle with the addition of but a small expense to cover the cost of the devices.

The section 12 may be folded in to rest upon the top surface of the bolster when not in use, or when an extraordinary width of the vehicle is not required, and the space between the abutment 20 and enlargement 23 may serve to center and support the end logs on the vehicle and prevent said logs from rolling off. The devices may furthermore be readily removed by withdrawing the studs 15 from the ends of the bolsters and the stakes may be reinserted in said openings 11.

While I have illustrated and described my invention with some degree of particularity, I realize that in practice various alterations

thereover may be made and I therefore desire to reserve the right and privilege of changing the form of the details of construction or otherwise altering the arrangement of the correlative parts without departing from the spirit of the invention or the scope of the appended claims.

Having thus described my invention what I claim as new and desire to secure by Letters Patent is:—

1. A device as set forth, in combination with a vehicle bolster, a wear plate on each terminal of the bolster, each wear plate being obliquely offset and terminating abruptly to provide a pocket at the end of the bolster, and an extension hinged on top of the wear plate and having one of its ends shaped to conform to the contour of said pocket and engaged therewith to serve as a support for the extension.

2. A detachable extension for bolsters in-

cluding a plate equipped with a stud for engagement with the bolster, and a body hinged to said plate and adapted to lie end to end with the bolster, when in an operative position, whereby the bolster will sustain said body against undue movement.

3. A detachable extension for bolsters including a plate, one face of which is extended to provide an integral stud, the stud being detachably mounted in the bolster, and an extension hinged on the plate and adapted to lie in the same horizontal plane with the bolster to serve as a continuation of the latter.

In testimony whereof I affix my signature in presence of two witnesses.

JAMES N. TREE.
